UNITED STATES PATENT OFFICE.

JOHN L. GAFFNEY, OF CHICAGO, ILLINOIS.

DESIGN FOR A MATCH-BOX HOLDER.

44,096.

Specification for Design.

Patented May 27, 1913.

Application filed November 15, 1912. Serial No. 731,609. Term of patent 7 years.

To all whom it may concern:

Be it known that I, JOHN L. GAFFNEY, a citizen of the United States, residing at Chicago, in the county of Cook and State of Illinois, have invented a new, original, and ornamental Design for Match-Box Holders, of which the following is a specification, reference being had to the accompanying drawing, forming a part thereof, in which—

I claim:

The ornamental design for a match box holder, as shown.

JOHN L. GAFFNEY.

Witnesses:

CHAS. C. TILLMAN,
A. S. PHILLIPS.
